[57] CLAIM

The ornamental design for a portable fan, as shown and described.

DESCRIPTION

FIG. 1 is a front elevational view of a portable fan showing our new design;
FIG. 2 is a top plan view thereof;
FIG. 3 is a rear elevational view thereof;
FIG. 4 is a bottom plan view thereof; and,
FIG. 5 is a left side elevational view thereof, the right side being substantially identical except for the control knob.

FIG. 1**FIG. 2****FIG. 3****FIG. 4****FIG. 5**
